(57) **CLAIM**

The ornamental design for a parts washer, as shown and described.

DESCRIPTION

FIG. 1 is a perspective view of a parts washer showing our new design;

FIG. 2 is a top plan view thereof;

FIG. 3 is a front elevation view thereof;

FIG. 4 is a side elevation view thereof;

FIG. 5 is a rear elevation view; and,

FIG. 6 is a bottom plan view.

The broken line showing of parts in FIGS. 1–6 is included for the purpose of illustrating environment and forms no part of the claimed design.

1 Claim, 6 Drawing Sheets
